UNITED STATES PATENT OFFICE.

DONATO DI CARLO, OF PHILADELPHIA, PENNSYLVANIA.

DESIGN FOR A SOUND-CONDUCTING DEVICE FOR TALKING-MACHINES.

55,986.

Specification for Design.

Patented Aug. 10, 1920.

Application filed June 17, 1920. Serial No. 389,768. Term of patent 14 years.

To all whom it may concern:

Be it known that I, DONATO DI CARLO, a subject of the King of Italy (having declared his intention of becoming a citizen of the United States), residing at Philadelphia, in the county of Philadelphia and State of Pennsylvania, have invented a new, original, and ornamental Design for a Sound-Conducting Device for Talking-Machines, of which the following is a specification, reference being had to the accompanying drawing, forming a part thereof, in which—

Figure 1 is a perspective view of a sound conducting device for talking machines, showing my new design, and

Fig. 2 is a side elevation of the device shown in Fig. 1.

I claim:

The ornamental design for a sound conducting device for talking machines, as shown.

DONATO DI CARLO.
